(57) **CLAIM**

The ornamental design for a self-righting paper clip holder, as shown and described.

DESCRIPTION

FIG. 1 is a front bottom perspective view of a self-righting paper clip holder showing my new design;

FIG. 2 is a front elevational view thereof, which is a mirror image of the back, left side and right side elevational views thereof;

FIG. 3 is a top plan view thereof;

FIG. 4 is a bottom plan view thereof; and,

FIG. 5 is a cross-sectional view thereof, taken along the lines 5—5 in FIG. 3.

The broken lines showing interior features depict environmental structure and form no part of the claimed design.
